DESIGN FOR WRAPPING PAPER OR THE LIKE

Berthold Kaufmann, Great Neck, N. Y.

Application December 9, 1940, Serial No. 97,175

Term of patent 3½ years

To all whom it may concern:

Be it known that I, Berthold Kaufmann, a citizen of the United States, residing in Great Neck, county of Nassau, State of New York, have invented a new, original, and ornamental Design for Wrapping Paper or the like, of which the following is a specification, reference being had to the accompanying drawing, forming part thereof.

The figure of the drawing is a plan view of a piece of wrapping paper or the like showing my design, the unit of which is indicated within the dot and dash lines.

I claim:

The ornamental design for wrapping paper or the like, as shown and described.

BERTHOLD KAUFMANN.
